UNITED STATES PATENT OFFICE.

CECIL VIVIAN USBORNE, OF WESTMINSTER, LONDON, ENGLAND.

APPARATUS FOR THE PROTECTION OF SHIPS AGAINST MINES AND THE LIKE.

1,355,718.

Specification of Letters Patent.

Patented Oct. 12, 1920.

Application filed February 2, 1918. Serial No. 215,221.

To all whom it may concern:

Be it known that I, CECIL VIVIAN USBORNE, a subject of the King of Great Britain, residing at United Service Club, Pall Mall, Westminster, in the county of London, England, have invented certain new and useful Improvements in Apparatus for the Protection of Ships Against Mines and the like, of which the following is a specification.

This invention has for its object the provision of apparatus for protecting ships against moored mines and like submerged bodies charged with explosives and adapted to be exploded by contact with the ship. To this end, according to the present invention the mines are caused to be deflected away from the path of the ship, and if desired, the mooring ropes connecting the mine to the sinker or other anchorage, cut.

The invention consists in a construction of body which is towed from the ship from a point preferably well down below the water line and which when in motion tows out from and to an extent downward with respect to the vertical plane containing the fore and aft line of the ship.

The invention further consists in the employment of wires trailing from the bodies with or without small kites or the like on the free ends of the wires.

The invention further consists in the constructional form of device employed on the ship, and also at or in the neighborhood of the kite whereby the towing wire and the kite can perform their desired functions in a satisfactory manner.

According to this invention the body which will be hereinafter referred to as a "kite" is constructed to accord more or less to the shape of the planes used on aircraft, that is to say with a cambered back surface, and a front surface which may be uniplanar or composed of two or more flat or curved surfaces, or a combination of both kinds of surfaces, the body being in general bluff pointed at the leading edge and of considerable taper toward the rear edge. The kites are provided if necessary with weights arranged low down, and with tail fins or rudders.

The kites are above described are employed either for deflecting mines, or for cutting the mooring ropes of the same, the two types of kites being respectively herein-

after referred to as deflecting kites and cutting kites. With the former type of kite, the moorings of mines are engaged by the cable towing the kite, and deflected away from the path of the ship, and it will be obvious that on the kite slipping the mine, it will return to its position and will still be a source of danger to other ships.

With the latter type the mooring is severed, whereupon the mine rises to the surface, disclosing its presence and is treated in any of the usual ways for destroying the same, whereby the section of a mine field within the sweeping area of the kites is destroyed and protection afforded not only for the ship effecting the severance of the mooring, but also other ships following the same course.

The accompanying drawings illustrate constructional forms of kites and auxiliary devices as hereinbefore referred to.

Figures 1 to 5 are more or less diagrammatic views corresponding to central horizontal sections of various forms of kites.

Fig. 6 is a top plan view of a deflecting kite.

Fig. 7 is a part sectional elevation of the kite shown in Fig. 6.

Fig. 8 is a vertical section on the line A—A of Fig. 7.

Fig. 9 illustrates the details of the ballast weight.

Fig. 10 is a plan view of a towing span used in the device illustrated in Figs. 6 and 7.

Fig. 11 is an elevation of the towing span, the cross section being shown at D—D and C—C.

Fig. 12 is a plan view of a cutting kite.

Fig. 13 is a part sectional elevation of the kite shown in Fig. 12.

Fig. 14 is a vertical section on Fig. 12 looking toward the forward end of the kite.

Fig. 15 is a longitudinal section of an anchorage for the towing wire.

Fig. 16 is a part sectional plan of sliding shoe fitting the stem of the ship.

Figs. 17 and 18 are part sectional elevations of the shoe shown in Fig. 16.

Figs. 19 and 20 are elevation and plan respectively of another form of fitting.

The forms of the kites illustrated comprise a cambered back surface 1 and a front surface 2 which may be uniplanar as shown in Fig. 1, or consist of two plane surfaces 110

at desired angles to the chord of the cambered back as in Figs. 2 and 3, or two curved surfaces as shown in Fig. 4 or a plurality of plane surfaces as shown in Fig. 5, such 5 superimposed parts giving increase in volume without altering the efficiency.

The front surface may however, if desired, be of a single curved surface of desired shape, or any desired combination of 10 plane and curved surface as will give efficient working.

The kites may be formed out of solid wood or built up of timber balks in any suitable way and preferably waterproofed, 15 or may take the form of a watertight hollow steel or metal body.

In the complete deflecting kite as shown in Figs. 6, 9, 10 and 11 the kite conforms to the shape shown in Fig. 1, and projecting 20 from the back surface 1 is a bracket 3 on or to which a weight 4 preferably of stream line form is adjustable secured; the bracket conveniently may comprise a metal plate 5 shaped as shown, supported from the back 25 surface 1 by stays 6, and flanges 7 at the rear end secured in any suitable way.

The kite is provided with a plurality of holes 8, for adjustment of the weight, which is secured in the desired position on the 30 plate 5 by bolts 9. Also the holes provide for additional weights to be added as required either for ballast or to alter the inclination to the vertical of the kite when swimming.

35 The kite may be provided with protecting metal plating 10 in the neighborhood of the leading edge, and where any fittings are to be secured, on parts which the mooring ropes of mines are likely to rub against.

40 To the upper and lower extremities of the leading edge of the kite means are provided for connecting the kite to the towing wire. This may conveniently consist of a metal plate 11 secured to and projecting beyond 45 the upper surface of the kite and a projecting plate 12 on the lower surface, this latter plate being either integral with the bracket plate 5 or formed of a separate plate secured in any suitable way. The upper and 50 lower plates are provided with apertures 13 for securing the kite to the towing connections hereinafter described. As shown in Fig. 7, the plates 11, 12 are connected together by a through bolt 14. The rear end 55 of the kite is provided with horizontal tail fins 15 acting as a vertical rudder, secured in any suitable way and if desired a horizontal rudder 15' may also be provided. The rudder 15' is supported by stays 15' or 60 hinged for adjustment. The fins and rudders damp out oscillation and assist in the depth-keeping of the kite.

The kite is towed by a span, bridle 17, or the like Figs. 10 and 11 of metal or other 65 material, pivoted or rigidly connected to,

or integral with the kite. The apex of the span is shackled to a tow anchorage for the towing wire the other ends of the limbs being pivoted on bolts passing through the apertures 13 in the plates 11, 12. In the 70 form of towing span shown in Figs. 10 and 11 a hollow metal body or casing 18 of stream line form is used containing a wood filling 19 to form the limbs or legs. The apex or common junction of the metal casings is provided with an aperture for securing a tow anchorage 20, Fig. 15, to which a towing wire is secured. The limbs are maintained apart by a stay 21 and the divergent ends of the metal casing are suitably formed 80 for connection to the plates 11, 12.

The shape of the tow anchorage, as will be hereinafter described, the inclination of the legs of the towing span and the connection to the kite are so arranged as to provide a 85 good lead for the mooring rope of the mine, from the towing wire to the kite and also to prevent the formation of any projections, undesirable excrescences, or reentrant portions, such as would retain the mooring rope 90 and cause the mine to tow with the kite.

The tow anchorage 20 Fig. 15 for this purpose consists of a hollow cone shaped body 22 of small angle and of metal or other suitable material having a bifurcated end 95 23 to engage over the apex of the towing span the two parts being secured together by the bolt. The cone is provided with a longitudinal bore 24 running from the smaller end for a considerable portion of 100 its length and leading into a chamber 25 of larger dimensions. Within the chamber is provided rubber buffers 26 and a metal cylinder 27 internally coned. The towing wire is led up the longitudinal bore 24 through 105 the rubber buffers 26 and into the metal cylinder 27 above referred to, the strands of the wire being opened out or splayed at the end so as to be contained within the cone shaped part of the cylinders. On the 110 splayed end of the wire occupying its correct position in the cylinder, liquid metal is run in so as to form a solid cone of metal and prevent withdrawal of the towing wire through the narrow end of the tow anchorage. A screwed plug 28 may conveniently be 115 inserted to keep the cylinder in position. The end of the tow anchorage through which the towing wire passes is cut at an angle of such magnitude as will cause the mooring 120 rope of the mine to pass easily from the towing wire to the tow anchorage and will not allow any abutment against which the mooring rope of a mine can be retained. If desired the longitudinal bore 24 of the anchorage may be lined with rubber.

The deflecting kite above described may, if desired, be provided with a length of cable, wire or the like which trails behind the kite when in motion to keep the mine de- 130

flected away from the ship's hull after the kite has slipped the mooring cable. The trailing wire is able to perform this function since the towing rope and kite are caused by the inward thrust of the mooring rope due to the displacement of the mine to move inward toward the ship to a certain degree but when the mine is slipped by the kite, the latter runs out to take up the normal position of running, with the result that the wire is also moved outward, or tends to move outward and so resists and overcomes the inward thrust of the mooring rope, sufficient to keep it deflected until such time as the mine can be slipped without coming into contact with the ship.

The trailing cable's end may, if desired, be provided with small kites of efficient form, either similar to the forms above described or of any other known form, to assist in keeping the trailing cable or the like well out or out and down.

When the form of protection according to my invention is to be applied to a ship having sufficient available power, the cutting form of kite is used. This form of kite may be of any of the shapes shown in Figs. 1 to 5. The form shown in Figs. 12 to 14 is similar to that shown in Figs 2 and 3 that is to say that with a cambered back surface 1 and a front surface 2, composed of two plane surfaces at desired angles to the chord of the cambered portion, forming a triangular prism superimposed on the chord. The front surface 2 may be provided with a wing or wings, vanes or the like extending above and below the kite, this wing portion being also of aeroplane section. The pressure of the fluid on these wings tends to increase the thrust obtained from the fluid, for a kite of given volume and dimensions. The back surface 1 of the kite is provided with a weight 4' arranged near the lower extremity and if desired the weight may be made adjustable and carried in a manner similar to that described with reference to Figs. 6 to 9.

The leading edge of the kite is provided with a curved guard 30 which may take the form of a metal bar or plate formed as shown. Secured to the kite in the neighborhood of the leading edge is a wire cutting device of any suitable character. The wire cutter is mounted in brackets or blocks 31 secured by stays 32, metal strengthening plates 33 being fixed if desired for securing the stays and cutter brackets. In the kite shown the wire cutting device is disposed on the longitudinal center line of the kite. The cutter supporting bracket or block 31 is provided with means for securing to the towing wire through the medium of a tow anchorage 20 as above described. The guard 30 and cutter supporting bracket 31 are so shaped as to give a good lead toward the

cutter so that the mooring rope of the mine is caused to be guided into the cutter jaws.

The rear end of the kite is provided with horizontal tail fins 15, a vertical rudder 16, to incline the front surface to a suitable angle for obtaining efficient thrust from the fluid, and an adjustable horizontal rudder 15' hinged to the bottom tail fin, and provided with a suitable clamping device for securing it in adjusted position.

The deflecting or cutting kites may if desired be provided with any known form of apparatus for automatically controlling one or more of the aforesaid rudders or additional rudders, to regulate the depth running of the kite, any displacement from the set depth line causing the apparatus to operate the rudder or rudders to bring the kite back to the set depth line.

Referring now to the fittings on the ship for towing kites as above described, a shoe 25 as shown in Figs. 16 to 18 comprises a section bar 36 bent or otherwise shaped to have an easy fit on the stem and stem bar 38 of the ship. The shoe is adapted to be raised and lowered by means of chains 39 which are shackled to the shoe and taken to a capstan, winch, or other winding gear on the ship. The shoe at its outer extremity is provided with enlargements, flanges, or like 35' provided with apertures 40 to receive a shackle to which the towing wire is connected by a tow anchorage similar to that above described although of course it is unnecessary to have the smaller end inclined as for the anchorage at the kite end of the towing wire. To enable the shoe to be suspended horizontally on the bow of the ship when pulled up above the water, and not in use, short lengths of chain 41 are fitted to carry the weight of the after part of the shoe. These lengths come slack when the shoe is in its working position.

The portions of the shoe engaging the stem of the ship are preferably outwardly flared as shown for ease in working up and down.

The working position of the shoe is arranged so that the point of attachment of the towing wires is kept as low down as the construction of the ship permits.

In the modification the shoe consists of a bracket like member with an outwardly and downwardly projecting limb to which the towing wire is shackled, and with the two side limbs or wings embracing the side of the ship, rollers, balls or like anti-friction device being provided between the bracket and stem of the ship. This form of shoe may be supported by chains as above described. With the latter form of shoe a lower point of tow can be arranged for, so that the point of tow can be nearly at the level of or below the ship's keel.

The supporting member in another form

consists of a flanged or otherwise shaped member to embrace the stem bar, and pivoted at its lower end to the ship in the region of the keel. The upper or outer end of the member is pivotally connected to one or more bars, rods or the like which in turn are pivotally connected to a sliding block, or other member adapted to be lowered and raised about the stem bar by suitable means, 10 such as for example, screw gear. With this form of apparatus, when the supporting member is not in use, the whole can be made to lie or fit close up against the stem of the ship, and not interfere with any other gear. This form has the advantage that it provides for the point of attachment of the 15 towing wire being low down and well forward.

Another type of fitting specially applied 20 cable for ships having a cut away forefoot is illustrated in Figs. 19 and 20, and consists of an outrigger or bridle, or the like 42 rigidly or pivotally mounted, preferably the latter to clump pieces or the like 43 secured 25 on the sides of the ship. The outrigger 42 may be formed of T section bars 44 bent in a manner similar to that shown in Fig. 20 having an outward curve in the vicinity of the stem of the ship, so as to clear the anchor and other fittings during movement of 30 any of the respective fittings. The outrigger is provided with a cross bar 45 having a reentrant bend 46 adapted to engage over the stem bar when the bridle is in the 35 working position.

Suitable cross bracing 47 is provided to strengthen the bridle.

To the extremity of the bridle is secured a plate, block or the like 48 provided with 40 apertures, or other means for shackling the towing wire.

An eye 49 is provided on the bridle to which a hauling chain 50 is shackled, the chain being taken to a fair lead 51 on the 45 deck, thence to a winch, capstan or other winding device.

In Fig. 19, the pivoted outrigger is shown in full line for the working position, and in dotted line for the position it occupies when 50 working the anchor, or when in the stowed position, these positions being respectively indicated at 42' and 42''.

The outrigger type of fitting provides for a point of tow being low down and well 55 forward with respect to the bows of the ship.

What I claim and desire to secure by Letters Patent of the United States is:—

1. A towed body for the protection of 60 ships, comprising a water kite the longitudinal section of which is of aeroplane wing section, the back surface being cambered and a towing connection at the nose of the kite adapted by its form to tow out from 65 the ship, for the purpose specified.

2. A towed body for the protection of ships, comprising a water kite of rectangular shape in elevation, the longitudinal section of which is of aeroplane wing section, the back section being cambered and a towing connection at the nose of the kite, which is adapted by its form to tow out from the ship for the purpose specified. 70

3. A towed body for the protection of ships, comprising a water kite the longitudinal section of which is of aeroplane wing section, said body having a cambered back surface and a projecting angular front surface of substantially triangular prism shape, and a towing connection at the end of the kite, which is adapted by its form to tow out from the ship, for the purpose specified. 80

4. A towed body for the protection of ships, comprising a water kite the longitudinal section of which is of aeroplane wing section, said body having a cambered back surface and a projecting angular front surface of substantially triangular prism shape, the faces of the projecting angular front being curved and a towing connection at the 90 end of the kite, which is adapted by its form to tow out from the ship, for the purpose specified.

5. A towed body for the protection of ships, comprising a water kite the longitudinal section of which is of aeroplane wing section, said body having a cambered back surface and a projecting angular front surface of substantially triangular prism shape, one of the faces of the projecting angular 95 front, at least, being curved and a towing connection at the end of the kite, which is adapted by its form to tow out from the ship, for the purpose specified.

6. A towed body for the protection of 105 ships, comprising a water kite the longitudinal section of which is of aeroplane wing section, said body having a cambered back surface and a projecting angular front surface consisting of a series of angular projections and a towing connection at the end of the kite, which is adapted by its form to tow out from the ship, for the purpose specified. 110

7. A towed body for the protection of ships, comprising a water kite the longitudinal section of which is of aeroplane wing section, said body having a cambered back surface and a projecting angular front surface consisting of a series of prism-shaped 115 projections and a towing connection at the end of the kite, which is adapted by its form to tow out from the ship, for the purpose specified.

8. A towed body for the protection of ships, comprising a water kite the longitudinal section of which is of aeroplane wing section, the back surface of the kite being cambered, said kite having positive buoyancy and weighted low down so as to displace the center of gravity sufficiently from the center 120 125 130

of buoyancy, to produce a large dynamic reaction and the body being displaced from its normal equilibrium position, whereby accurate depth keeping is insured.

5 9. A towed body for the protection of ships, comprising a water kite the longitudinal section of which is of aeroplane wing section, the back surface being cambered, said kite provided with a tail fin for damping oscillation and a towing connection at the nose of the kite, which is adapted by its form to tow out from the ship, for the purpose specified.

10 10. A towed body for the protection of ships, comprising a water kite the longitudinal section of which is of aeroplane wing section, the back surface being cambered, said kite provided with a tail fin for damping oscillation, an adjustable rudder 20 on said fin and a towing connection at the nose of the kite, which is adapted by its form to tow out from the ship, for the purpose specified.

11 11. A towed body for the protection of ships, comprising a water kite the longitudinal section of which is of aeroplane wing section, the back surface being cambered, a plane extending beyond the upper and lower faces of the body whereby the 30 outward thrust obtained from the fluid is increased with respect to the total volume and weight.

12 12. A towed body for the protection of ships, comprising a water kite the longitudinal section of which is of aeroplane wing section, the back surface being cambered, a vertical rudder so set, relatively to the body, that the pressure on the rudder due to towing, inclines the front surface of the 40 body to an angle which allows of the efficient thrust from the fluid.

13 13. A towed body for the protection of ships, comprising a water kite the longitudinal section of which is of aeroplane wing section, the back surface being cambered, said kite connected by a span extending from the nose of the body to the towing member, whereby the mooring of the mine, engaged by the towing member, is deflected 50 and subsequently slipped by the body.

14. A towed body for the protection of ships, comprising a water kite the longi-

tudinal section of which is of aeroplane wing section, the back surface being cambered, a trailing wire for the kite and 55 means for towing said kite.

15. A towed body for the protection of ships, comprising a water kite the longitudinal section of which is of aeroplane wing section, the back surface being cambered, a cutting device for said kite and means by which the mooring rope of the mine is led into the cutter and severed.

16. A towed body for the protection of ships, comprising a water kite the longitudinal section of which is of aeroplane wing section, the back surface being cambered, and a towing connection at the nose of the kite comprising a slightly coned sleeve, a central bore in said sleeve, an enlargement in the bore, an internally coned cylinder and a resilient buffer situated in said enlargement, adapted to receive the conical end of the towing cable positioned inside of said cylinder.

17. A towed body for the protection of ships, comprising a water kite the longitudinal section of which is of aeroplane wing section, the back surface being cambered, said kite provided with rudders and with automatic apparatus controlling at least one rudder adapted to regulate accurately the depth at which the kite runs and to bring the kite back to the set depth line, 80 on displacement therefrom.

18. A towed device for the protection of ships, comprising a series of water kites, the longitudinal section of each of which is of aeroplane wing section, the back surfaces of the kite being cambered and a connection at the nose of each kite adapted by their form to tow out from the ship for the purpose specified.

19. A towed device for the protection of ships, comprising a series of water kites, the longitudinal section of each of which is of aeroplane wing section, the back surfaces of the kite being cambered, trail wires for said kites and a towing connection at the nose of each kite adapted by their form 100 to tow out from the ship for the purpose specified.

CECIL VIVIAN USBORNE.
